United States Patent Office

Des. 204,702
Patented May 10, 1966

204,702

JUG

John V. Nixon, Lancaster, Ohio, assignor to Anchor
Hocking Glass Corporation, Lancaster, Ohio, a corpo-
ration of Delaware

Filed Sept. 2, 1965, Ser. No. 86,808

Term of patent 14 years

(Cl. D58—5)

FIGURE 1 is a perspective view of a jug showing my new design;

FIGURE 2 is a side elevational view thereof;

FIGURE 3 is a rear elevational view thereof; and

FIGURE 4 is a top plan view thereof.

The dominant feature of my design resides in the portions shown in full lines.

I claim:

The ornamental design for a jug, substantially shown and described.
